MULTIUNIT RADIO RECEIVING SYSTEM

Raymond Kimball, Hollywood, Calif.

Application July 3, 1937, Serial No. 151,897

19 Claims. (Cl. 179—1)

This invention is a radio receiving system providing for selectively controlled intercommunication among a plurality of inter-related stations.

One of the objects of the invention is to provide a system of the character mentioned characterized by a plurality of inter-related radio receiving stations and means selectively controllable at each of said stations for establishing oral communication with any one of the other stations. A further object is to provide simple means for temporarily converting the sound reproducing element of any station into a microphone and placing it into communication with the sound reproducing element of any other station of the system. A further object is to provide means at each station for selectively effecting temporary interruption of radio reception at any of the other stations of the system.

The invention will be hereinafter fully set forth and particularly pointed out in the claims.

In the accompanying drawings,

Figures 1, 2, 3 and 4 are diagrammatic views of a corresponding number of portions of the radio receiving system, it being understood that all of them are part of a single lay-out and should be regarded as assembled in joint relation as one larger complete plan, with Figure 2 at the right of Figure 1 and Figures 3 and 4 below Figures 1 and 2 respectively.

Referring to the drawings, A diagrammatically illustrates a program power-supply-control device of the type provided with means controllable from a distance for making and breaking the circuit to the various tuners and amplifiers of the system. B indicates an intercommunicating power supply device having means controllable from a distance for establishing intercommunication between control stations. C represents an amplifier controllable from a distance for amplifying intercommunication between stations. D is a transformer for reducing the usual 110 volt power current to a 6 volt power supply.

Any number of stations may be employed, each with its duplicated control devices and loud speaker, four of such stations, located in separate rooms, being shown for purposes of illustration. The several stations are represented by panel boards CP¹, CP², CP³, and CP⁴, respectively, each provided with circuit closing devices and wiring, all to be described in detail later. The circuits and method of control are identical in each instance, except that the circuit closing devices carried by panel boards CP¹ and CP² are illustrated as of the push button type and those

of panel boards CP³ and CP⁴ are of the rotatable gang switch type. The panel boards may be of the portable type or of the fixed wall type, the push button controls being preferably used with the portable type CP¹ and CP² and the gang switch being preferably carried by the fixed wall type CP³ and CP⁴.

The main lead-in wire *a* is connected by a branch wire 20 to the program power supply A, by a branch wire 21, to the intercommunicating power supply B by wire 21^a, and is also directly connected with the transformer D. Leading from the intercommunicating power supply B is a wire 22 to which is connected the fixed contact *r* of each of a series of relays #10, #11, #12 and #13 respectively. Leading from the program power supply is a wire 23 which by means of a wire 24 is connected to the fixed contact *r* of each of relays #14, #15 and #16. Each relay #14 and #15 is provided with two sets of contacts, namely one set consisting of a fixed contact *r* and a movable contact *s*, and the other set consisting of a fixed contact *o* and a movable contact *o'*. The two movable contacts are so connected as to move together. All of said relays #10, #11, #12, #13, #14, #15, and #16 have their movable contacts *s* suitably connected with a return wire 25, which in turn is connected by a wire 26 to the main return wire *b*. Contact *o* of each relay #14 and #15 is connected with the wire 28. Contact *o'* of relay #14 is connected with wire 128 by wire 128^a and contact *o'* of relay #15 is connected to wire 127 by wire 38.

Each of the coils of the respective relays #10, #11, #12, #13, #14, #15 has one terminal connected with a common feed wire 28, which in turn is connected to the output side of transformer D, by wire 29. The circuit connections with the other terminals of said coils will be described later in connection with the detail description of the respective control stations.

The intercommunicating power supply B is so constructed that the circuit to wire 21^a and its connections is normally broken, said circuit being closed, however, upon the actuation of any one of the relays #10, #11, #12 and #13. It will be observed that the fixed contact *r* of each of these relays is connected with the wire 22 and that the movable contact *s* of each relay is connected with the return wires 25 and 26.

In addition to the relays above described there is another group of relays arranged in pairs, to wit, #1 and #2, #3 and #4, #5 and #6, and #7 and #8, each having two fixed contacts, *s*, *s'* and a movable contact *s*². The fixed contact *s*

of each relay #1, #3, #5 and #7 is connected to a common wire 28^a. Each fixed contact *s*' of relays #1, #3, #5 and #7 is connected with the movable contact *s*² of relays #2, #4, #6, #8, respectively. Each fixed contact *s* of relays #2, #4, #6, #8, is connected to a common wire 28^b. The movable contacts *s*² of each relay #1, #3, #5 and #7 is connected with a wire 106 leading to a loud speaker, one for each control station, relay #1 being connected with LS' of control panel CP', relay #3 with LS² of CP², relay #5 with LS³ of CP³ and relay #7 with LS⁴ of CP⁴. Each loud speaker is also connected by wire 107 with wire 39. The fixed terminal *s*' of relay #2 is connected with amplifier AM' by wires 103 and 103^a, 104, *s*' of relay #4 is connected with amplifier AM² by wires 108, 109, 110, *s*' of relay #6 is connected directly with amplifier AM³ by wire 112, and *s*' of relay #8 is directly connected 20 with amplifier AM⁴ by wire 112^a and 114.

One end of the coil of relay #1 is connected to a terminal of the coil of relay #10, by means of a wire 30, said last-mentioned wire being also connected with conductor 118. In a similar manner a terminal of coil of relay #3 is connected to a terminal of the coil of relay #11 by means of wire 31, said wire also being connected with conductor 125, a terminal of the coil of relay #5 is connected with a terminal of the coil of relay #12 by wire 32 which wire is also connected with conductor 125; and a terminal of the coil of relay #7 is connected with a terminal of the coil of relay #13 by a wire 123^a which wire is also connected with conductor 127. Each of the 30 other terminals of the coils of relays #10, #11, #12 and #13, as before stated are connected with the transformer wire 29 by wire 28.

One terminal of the coil of relay #2 is connected with conductor 117 by a wire 117^a; one terminal of the coil of relay #4 is connected with conductor 119 by a wire 119^a; one terminal of the coil of relay #6 is connected with conductor 122 by a wire 122^a; and one terminal of the coil of relay #8 is connected with a conductor 123 by a wire 123^a.

The portable control panel CP' is provided with a plurality of diagrammatically illustrated switches P¹, P², P³, P⁴, P⁵, P⁶, P⁷, P⁸, P⁹, P¹⁰, P¹¹, P¹², preferably in the form of push buttons. Push button P² which is the on-off button, has one terminal *p* connected to a terminal of the coil of relay 15 by means of conductors 35, 36 and 37 the other terminal of said coil being connected with the ground wire 28. The movable contact *o*' of relay 15 is connected to a pilot light L by means of wire 38, 127, 40, said light being grounded by wire 41 in any suitable manner. Thus, the pilot light is illuminated when the relay 15 is in one position.

Relay #15 is the "on-off" power supply for CP'. It is of the pulsating type, operating one way on the first impulse and returning to its normal position on the second impulse. The construction of the relay is such that the life of the pulsation is not a factor in the operation of the system.

Any number of radio tuners and amplifiers may be employed but for purposes of illustration four tuners RT', RT², RT³, and RT⁴, and a phonograph amplifier one for each control panel, and four individual station amplifiers AM', AM², AM³ and AM⁴ are shown.

Located at a convenient position is relay #9 one terminal of the coil thereof being connected 75 with wire 28 by wire 27^a, the other terminal be-

ing connected with wire 116 by wire 116^a. This relay is provided with two sets of contacts *t*, *t*², *u*, *u*². Contacts *t*, *t*², *u* and *u*² are fixed and contacts *t*² and *u*² are movable and so connected as to operate in unison. Fixed contacts *t* and *u* are connected by wire *t*³ with the input of intercommunicating amplifier C. The input of amplifier C is also connected with wire 39 by a wire *t*⁴. Fixed contacts *t*² and *u*² are connected by means of a wire *u*⁴, to the output of amplifier C. The output of amplifier C is also connected with wire 39 by wire *u*³. The movable contact *u*² is connected by wire *t*⁵ with wires 28^a and movable contact *t*² is connected by a wire *u*⁵ with wire 28^b.

The radio tuners and amplifiers all receive their operating voltages from the common program power supply A by means of wire 45 leading from the latter, and having a branch wire 46 connected with amplifier AM⁴, the respective amplifiers AM³, AM² and AM' also being connected by wires 47, 48 and 49 respectively. Supply wire 45 is also connected with a branch wire 50 leading to radio tuners numbered RT⁴ and RT⁵ respectively, radio tuner RT⁶ being connected with the phonograph amplifier AM⁵ by means of a wire 51. Tuners RT¹, RT², RT³ and RT⁴ are connected by suitable wires 52, 53 and 54 respectively. Leading from the antennae ANT is a wire 55 which is connected by branch wires 56 with the respective tuners as shown. Each of the radio tuners is provided with circuit wires *d*', *d*², respectively, said circuit wires of tuner RT¹ being connected with line wires 60, 61 respectively, the circuit wires *d*', *d*² of tuner RT² being connected with wires 62 and 63, wires *d*', *d*² of RT³ being connected with wires 64, 65, wires *d*' *d*² of RT⁴ being connected with wires 66, 67 and wires *d*', *d*² of RT⁵ being connected with wires 68, 69. The phonograph amplifier AM⁵ is connected by 40 branch wires *d*³, *d*⁴ with the wires 70 and 71 and is also connected by suitable circuit wires 72^a with the phonograph pick-up F. Wires 72, 73, 74 and 75 are dead wires and are only to be used in the event that it is desired to increase the 45 number of tuners.

Leading from the wire *a* is a branch wire 76 which is connected to one side of the phonograph motor G, the other side of said motor being connected by means of a wire 77 to contact *s* of the 50 relay #17. The other contact *r* of relay 17 is connected through the wires 27 and 26 to the wire *b*.

Assuming that it is desired to tune in on any desired program at station CP', the "on-off" button P² is depressed, thereby closing the circuit from transformer D via wire 29, wire 28, coil of relay #15, wires 37, 36 and 35, contacts *p*, *p*' of switch P², wires 48^a, 39 and 48^b to transformer D. As the coil of relay #15 is energized contacts 60 *r* and *s* of said relay are brought into engagement, thereby closing a circuit from main input conductor *a*, wire 20, program power supply A, wire 23, contacts *r*, *s* of relay #15 and return through wires 27 and 26 to return wire *b*. Operation of relay #15 also closes a circuit from transformer D, through wires 29, 28, contacts *o*, *o*' of relay #15, wires 38 and 40, pilot light L, wires 41, 41^a to ground.

Current passing through program power supply 70 A by reason of closing of the circuit through relay #15 connects the main power line *a* with wire 45 in a manner well understood in the art.

Any one of the five program selector buttons, i. e. buttons P⁸, P⁹, P¹⁰, P¹¹, P¹² is pressed down- 75

wardly for selection of a radio and button P^7 is pressed downwardly for selection of phonograph program. Each of said program selector switches has four contacts x , x' , x^2 and x^3 respectively, connected to the output of its corresponding radio tuner or the phonograph. The contact x^3 of button P^{12} is connected with the wire 61 by means of a wire 60 and the contact x of that switch is connected with the wire 60 by means of a wire 81 .
 5 In a similar manner, the contact x of each of the switches P^{11} , P^{10} , P^9 , P^8 , P^7 are respectively connected by wires 82 , 88 , 89 , 86 and 90 with the respective wires, 62 , 64 , 66 , 70 and 68 and the contacts x^3 of said switches are connected with the wires 63 , 65 , 67 , 71 , 69 , respectively by wires 87 , 83 , 84 , 91 and 85 , respectively, thereby placing tuner RT^1 under the control of switch P^{12} , the tuner RT^2 under the control of switch P^{11} , the tuner RT^3 under the control of switch P^{10} , the tuner RT^4 under the control of switch P^9 , the tuner RT^5 under the control of switch P^8 and the phonograph amplifier under the control of switch P^7 .
 10 With the buttons of the program selector switches in the top or open circuit positions, 25 dummy load resistors R are arranged across the respective tuner or phonograph output circuits. Each resistor is equal to the input impedance of the room amplifier. When any program selector button is depressed, the dummy load resistor of
 20 that particular switch is disconnected from the tuner circuit and the output of the program channel is connected through to the volume control VC^1 . Contact x^2 of each button is connected with the volume control by wire $80x$ and contact
 25 x' is connected to ground by wire $41x$. One side of the volume control VC^1 is connected by wire 100 to amplifier AM^1 , the other wire 101 from said amplifier being grounded through the ground wire 41 . In the case of the station CP^1 the output
 30 line is to the amplifier AM^1 as stated. In a similar manner amplifier AM^2 is connected with the portable station CP^2 and the amplifiers AM^3 and AM^4 are respectively connected in a similar way to the respective stations CP^3 and CP^4 .
 35 One side of the output of each amplifier AM^1 , AM^2 , AM^3 and AM^4 is connected by means of a wire 102 with the common ground wire 39 . The other side of the output of amplifier AM^1 is connected by means of wires 103 , $103a$ and 104 to contact s' of relay #2.
 40 While relays #1 and #2 are in normal or off position the circuit will be through contacts s' , s^2 of relay #2, wire 105 , contacts s' , s^2 of relay #1, and wire 106 to speaker LS^1 , and return by wire
 45 107 which is connected to the ground wire 39 . The other side of amplifier AM^2 is connected by wires 108 , 103 and 110 , relays #4 and #3 which in the off position of the relays connects with the speaker LS^2 through its wire 106 , the return wire
 50 107 of said speaker being connected to ground wire 39 . In a similar manner, the terminals of relays #5 and #6 are placed in circuit with LS^3 by wires 112 , $105b$, 106 , 107 and 39 ; and the terminals of relays #7 and #8 are placed in circuit with
 55 SP^4 by wires $112a$, $105c$, 106 , 107 and 39 . Each pair of relays #1 and #2, #3 and #4, #5 and #6, and #7 and #8 are intercommunicating relays and have no bearing on the program reproduction other than to cut it off when the intercommunication system is being used.
 60 The portable control CP^1 has an interlocking device I on all intercommunication selector buttons P^3 , P^4 , P^5 , P^6 , and all program selector buttons P^7 , P^8 , P^9 , P^{10} , P^{11} and P^{12} . This interlocking device is so arranged in a manner well understood

in the art, that when any of the above mentioned buttons is depressed, it will be locked down until another button is depressed, whereupon the first button is released and the second button locks down. Devices of this type are very common and it is not considered necessary to illustrate this type of device in detail. The two topmost buttons P^1 and P^2 of the 12 button control are disconnected from the interlocking device so that they do not lock down while depressed.

Each control station in the form of the invention illustrated is provided with 12 circuit closers. For instance, on control board CP' twelve push buttons are shown, the button P' being the "press-to-talk" button which functions to reverse the input and output of the inter-communication amplifier by the operation of relay #9, setting up the calling speaker and the speaker which is being called alternately as microphone and reproducer. The push button P^2 is the "on-off" button which is pressed to initiate or terminate the radio reception and to start or stop the normal radio reception functions of the system. Buttons P^3 , P^4 , P^5 and P^6 are the calling or selector buttons for the inter-communication system, one for each station on the system, P^3 being out of use. By means of these buttons, the loud speakers at the respective stations may be selectively disconnected from the various amplifiers. For instance, the button P^4 controls the amplifier AM^1 for loud speaker LS^4 ; button P^5 controls amplifier AM^2 for loud speaker LS^2 ; button P^6 controls the amplifier AM^3 for loud speaker LS^3 ; button P^3 is an extra intercommunication selector button and would normally be unconnected as shown or connected to an extra station. The button P^7 controls the phonograph motor through relay #17 as follows: Depression of said button closes a circuit from transformer D, wires 29 , 28 , $17x$, coil of relay #17, wires $122a$, 121 , $17a$, contacts $17b$, $17c$, wires $17d$ and $41a$ to ground. By energizing the coil of relay #17 circuit is closed by contacts r , s of said relay through wires 76 , phonograph motor G, wires 71 , 27 , 26 and b .

Upon the depression of the button P' , circuit is closed from the transformer D through the wires 29 , 28 , $27a$ and the coil of relay #9, wires $116x$, 116 , $116a$, the contacts of P' , and wires $40a$, 39 , $40b$ back to transformer D. Thus, the coil of relay #9 is energized so that the movable members t^2 and u^2 of said relay are shifted in such a manner as to reverse the connections of the sound reproducer LS' , and which ever of the reproducers (LS^2 , LS^3 , or LS^4) may be in the circuit due to selection by depressed buttons P^4 , P^5 , or P^6 , from the input to the output of the inter-communication amplifier.

Assuming that a person in the room where control panel CP' is located is desirous of communicating with the person in the room where control panel CP^3 is located, he will first depress the calling button P^6 which is the proper button to reach station CP^3 . Depressing of the button P^6 will close a circuit from transformer D via wires 29 , 28 , coil of relay #10, wires 30 , 118 , 151 , $151y$, $151x$, contacts v^2 and v^3 of button P^6 and return to transformer D by wires $40a$, 39 , and $40b$. The energizing of relay #10 closes a circuit through the intercommunication power supply B so that power is furnished to the inter-communication elements of the system. Simultaneously, a circuit is also established from transformer D via wire 29 , coil of relay #6, wire $122a$, contacts v , v' of button P^6 and wires $151x$, $40a$, 39 and $40b$ to the transformer. At the same

- time another circuit is established from the transformer D via wires 29, 28 and 27^a, coil of relay #1, wires 30, 118, 151, 151^a, contacts v³, v² of button P⁶, and wires 151^a, 40^a, 39, 40^b to D. 5 It will be observed that when the coil of relay #6 is energized the movable contact s² is moved out of engagement with the fixed contact s' and engages the contact s, thereby cutting out the amplifier AM³.
- 10 The energizing of the coil of relay #1 shifts the movable contact s² of that relay out of engagement with contact s' thereby breaking the circuit at these contacts and bringing contacts s² and s into engagement, thereby breaking the 15 normal circuit to loud speaker LS' and so connecting the latter with the intercommunicating amplifier C that the connections to the loud speaker LS' must pass through the contacts of relay #9. The circuit will now be from the intercommunicating amplifier C through wires u⁴, u, u², 28^b, 27^a, contacts s and s² of relay #2 and to loud speaker LS' through wire 105, relay #1 to wire 106. At the same time circuit is established by relay #9 through wires t³, contacts t, t², wires u⁵, 28^a, 113, contacts s', s² of relay #5 and wire 106 to loud speaker LS³ on control panel CP³.

By the foregoing changes, loud speaker LS' is now made to function as a reproducer and loud speaker LS³ is functioning as a microphone, so that the person at control board CP' is listening in to the room in which loud speaker LS³ is located, i. e. at control board CP³. Relay #9 normally functions to reverse the speakers which may have been placed in circuit therewith from the input to the output of the intercommunication amplifier C. Before the person at control board CP' may talk and be heard through the loud speaker LS³, he must first press the "press-to-talk" button P' on his control panel CP'. Normally, the circuits through the relay #9 are connected with the output of the intercommunication amplifier C. Energizing of the coil of relay #9 shifts the movable contacts t² and u² so as to connect the speakers with the input and output of the intercommunication amplifier in the reverse order of the normal circuits above described. A conversation may then be carried on by the originator of the call pressing the button P' while talking, and releasing it while listening. It will, of course, be understood that through the operation of the relays #1 and #6 as just described, the programs, if any, which are being produced through speakers LS' and LS³ are completely cut off while the conversation takes place, and that when the intercommunication selector switch P⁶ is returned to normal position the programs originally being produced at both stations are replaced.

The arrangement of the circuits is such that any person at any one of the stations CP', CP², CP³, CP⁴ may selectively communicate with any one of the other stations of the group by merely depressing the proper button P⁴, P⁵ or P⁶ as the case may be, and operating the button P' as above described. For instance, by depressing the button P⁴ the coils of relays #1, #7, #8 and #13 are energized so as to close the circuit through 70 intercommunicating power supply B, to cut out amplifier AM⁴, and to place speakers LS' and LS⁴ in communication. The power circuit is closed by relay 13, and the amplifier AM⁴ is cut out by the operation of relay #8. Relay #2 functions 75 as has already been described in connection with

the intercommunication between stations 1 and 2. Speakers LS' and LS² are connected by depressing button P³ thereby closing the power circuit through relay #11, cutting out the amplifier AM² and connecting the speakers with the 5 intercommunicating amplifier C as already described, through relays #3, #2 and #9.

The modified form of control employed in connection with the fixed wall-type panel as illustrated in connection with station CP³ preferably 10 comprises four switch contact disks E¹, E², E³ and E⁴ secured to a rotatably mounted shaft E⁵, so that they may be actuated as a gang. In a similar manner, a two disk gang switch having contact disks E⁶ and E⁷ is provided, the same 15 being mounted on shaft E⁸. All of the switches are shown in "off" position. Switches E³ and E⁴ are for program selection, switches E⁶ and E⁷ are for intercommunication control, and E⁹ designates a press-to-talk switch. 20

Program selector disk E³ is provided with six contacts arranged to engage terminals of wires 200, 201, 202, 203, 204 and 205, the other terminals of which are respectively connected with wires 60, 62, 64, 66, 68 and 70. Disk E⁴ is also 25 provided with six contacts arranged to engage terminals of wires 200^a, 201^a, 202^a, 203^a, 204^a and 205^a, the other terminals of which are connected with wires 61, 63, 65, 67, 69 and 71. Dummy resistors 206 similar to those shown on panel 30 CP' may be provided.

Plate E¹ which is the phonograph "on and off" switch, contains six contacts which are selectively brought into engagement with one terminal of a wire 207, the six contacts corresponding to the 35 positions of said disk when rotated with shaft E⁵. The other terminal of wire 207 is connected with wire 121 so as to be placed in circuit with the coil of relay #17 whereby the latter may be caused to function in the same manner as described 40 in connection with push button P⁷.

Plate E² cooperates with the "power on-off" switch E⁹. Said plate is provided with six contacts corresponding to the number of positions of the disk when rotated with disks E³ and E⁴, so that at least one of a plurality leads 208 is at 45 all times in engagement with a contact. Leads 208 are connected with a wire 209 the other end of which is connected to wire 124 so as to control the circuit to coil of relay #16. Closing the circuit through any of the leads 208 establishes a 50 circuit from transformer D, wires 29, 28, coil #16, wires 125, 124, 209, switch E², wires 211, 39, 49^b to transformer D. Relay #16 closes circuit from program power supply A via wires 23, 27^a, contacts r, s, wires 27, and 26 to return wire b. One terminal of switch E⁹ is connected with disk E² by wire 210, and said last mentioned wire is connected with wire 39 by means of a wire 211. The other terminal of switch E⁹ is connected by a wire 212 with wire 116. The operation of switch E⁹ is the same as that already described in connection with switch P'.

Disk E⁶ and E⁷ are each provided with four active contacts corresponding to the number of 65 stations in the system. The contacts of disk E⁶ are arranged to engage terminals of wires 215, 216, 217 and 218, respectively. The other ends of said wires are connected respectively with wires 117, 119, 122 and 123. The contacts of disk E⁷ 70 are all connected to leads 219 connecting with one terminal of the wire 220 the other terminal of which is connected with wire 126. The circuits are the same as heretofore described in connection with push buttons P³, P⁴, P⁵ and P⁶. 75

The advantages of the invention will be readily understood by those skilled in the art to which it appertains. For instance, it will be observed that very simple and effective means is provided for oral intercommunication between any two stations of a multistation receiving system without in any manner disturbing the normal functions of any of the other stations. A further advantage is that just as soon as the temporary interruption for intercommunication between stations ceases said stations will automatically reestablish the interrupted radio reception.

It is to be understood that for purposes of illustration, the intercommunication sound control herein disclosed has been described as applied to a multiunit radio receiving set, but that the invention is not limited to this particular use because it is equally adapted for use in association with television, or any other intercommunication sound reproducing system.

Having thus explained the nature of the invention and described an operative manner of constructing and using the same, although without attempting to set forth all of the forms in which it may be made, or all of the forms of its use, what is claimed is:

1. A multiunit radio receiving system comprising a plurality of receiving units operatively connected with a radio receiving circuit, each unit including a sound reproducing device and its circuit, an intercommunication power circuit means common to all of said receiving units, means selectively controllable at each unit for connecting the sound reproducing device of the same unit and the sound reproducing device of any other preselected unit with said intercommunication power circuit, and means associated with each unit for changing the direction of current flow through its sound reproducing device and the preselected sound reproducing device while said devices are included in said intercommunication power circuit.

2. A multiunit radio receiving system comprising a plurality of receiving units operatively connected with a radio receiving circuit, each unit including a sound reproducing device and its circuit, an intercommunication power circuit means common to all of said receiving units, means selectively controllable at each unit for disconnecting the sound reproducing device of that unit and of any other preselected unit from their respective circuits, said means also including means for connecting the said two sound reproducing devices with said intercommunication power circuit simultaneously with the breaking of the sound-reproducing circuits, and means controllable at each station for reversing the direction of current flow through said two sound reproducing devices while the latter are connected with said intercommunication power circuit.

3. A multiunit radio receiving system comprising a plurality of receiving units operatively connected with a radio receiving circuit, each unit including a sound reproducing device and its circuit, an intercommunication power circuit means common to all of said receiving units, means selectively controllable at each unit for connecting the speaker of the same unit and the speaker of any other preselected unit with said intercommunication power circuit, means associated with each unit for changing the direction of current flow through its sound reproducing device as well as the sound-reproducing device of the preselected unit, while they are included in said intercommunication power circuit, and

means for connecting said intercommunication power circuit with a source of electrical energy simultaneously with the interruption of the normal current flow through the sound reproducing devices.

4. A multiunit radio receiving system comprising a plurality of receiving units operatively connected with a radio receiving circuit, each unit including a sound reproducing device and its circuit and a plurality of program selection devices, means for controlling the volume of selected program reproduction, an intercommunication power circuit means common to all of said receiving units, control means associated with each unit for disconnecting the sound reproducing device of the same unit as well as the sound reproducing device of any other preselected unit from the program selection means, means controllable at each unit for connecting the sound reproducing device of the same unit and the sound reproducing device of the preselected unit with said intercommunication power circuit, and means associated with each unit for changing the direction of current flow through the sound reproducing devices while the latter are included in said intercommunication power circuit.

5. A multiunit radio receiving system comprising a plurality of receiving units operatively connected with a radio receiving circuit, means providing a normal amplifier circuit for each unit, a sound reproducing device associated with each unit and included in the normal amplifier circuit of the same unit, an intercommunication power circuit means common to all of said receiving units, means providing an intercommunication amplifier circuit connected with said intercommunication power circuit and also connected with the several normal amplifier circuits of the respective units, means selectively controllable at each unit for disconnecting the sound reproducing device of the same unit from its normal amplifier circuit and also disconnecting the sound reproducing device of any other preselected unit from its normal amplifier circuit, said selective means also including means for connecting said disconnected sound reproducing devices with said intercommunication amplifier circuit, and means associated with each unit for changing the direction of current flow through its sound reproducing device and the preselected sound reproducing device while said devices are included in said intercommunication amplifier circuit.

6. A multiunit radio receiving system comprising a plurality of receiving units operatively connected with a radio receiving circuit, means providing a normal amplifier circuit for each unit, a sound reproducing device associated with each unit and included in the normal amplifier circuit of the same unit, an intercommunication amplifier circuit means common to all of said receiving units, means for breaking each of said normal amplifier circuits, means for connecting each sound reproducing device to the intercommunication amplifying circuit, means at each circuit for controlling the circuit breaking means of its amplifier circuit and the connecting means of the sound reproducing device of any other preselected unit with said intercommunication amplifier circuit, and means associated with each unit for changing the direction of current flow through the sound reproducing device of the same unit and also through the preselected sound reproducing device while said devices are included in said intercommunication amplifier circuit.

7. A multiunit radio receiving system comprising a plurality of receiving units operatively connected with a radio receiving circuit, means providing a normal amplifier circuit for each unit, 5 a sound reproducing device associated with each unit and included in the normal amplifier circuit of the same unit, an intercommunication amplifier circuit means common to all of said receiving units, means for breaking each of said 10 normal amplifier circuits, means for connecting each sound reproducing device to the intercommunication amplifier circuit, means for connecting said intercommunication amplifier circuit with a source of current supply, means at each 15 unit for controlling the circuit breaking means of its amplifier circuit and for controlling the connecting means of the sound reproducing device of any other preselected unit with said intercommunication amplifier circuit, and also for 20 controlling the means for connecting the intercommunication amplifier circuit with said source of current supply, and means associated with each unit for changing the direction of current flow through the sound reproducing device of the 25 same unit and also through the sound reproducing device of any preselected unit while said devices are included in said intercommunication amplifier circuit.

8. A multiunit radio receiving system comprising a plurality of receiving units operatively connected with a radio receiving circuit, each unit including a sound reproducing device and its circuit, an intercommunication power circuit means common to all of said receiving units, means at 30 35 each unit for breaking the circuits of the sound reproducing device of the same unit, and also for breaking the sound reproducer circuit of the sound reproducing device of any other preselected unit, means for connecting the disabled sound reproducing devices with said intercommunication power circuit, a common control means associated with each unit for simultaneously actuating the means for breaking the said sound reproducer circuits and the means for connecting the disabled sound reproducing devices with the intercommunication power circuit, and means associated with each unit for changing the current flow through the sound reproducing device of the same unit while the previously disabled sound reproducers are connected with said intercommunication power circuit.

9. A multiunit radio receiving system comprising a plurality of receiving units operatively connected with a radio receiving circuit, each unit including a sound reproducing device and its circuit, an intercommunication power circuit means common to all of said receiving units, a relay controlling said intercommunication power circuit, said relay having reversing contacts, means associated with each unit for breaking the first mentioned sound reproducer circuit of said unit, means associated with each unit for connecting one terminal of its sound reproducing device with said relay, means at each unit for actuating the circuit breaking means of the sound reproducer circuit of the same unit and the sound reproducer circuit of any other preselected unit, and means associated with each unit for energizing said relay so as to reverse the normal flow of the 60 65 70 current through said intercommunication power circuit and the sound reproducing devices connected therewith.

10. A multiunit radio receiving system comprising a plurality of receiving units operatively connected with a radio receiving circuit, each unit

including a normal amplifier circuit and a sound reproducing device in said circuit, an intercommunication amplifier circuit means common to all of said receiving units, a relay having reversing contacts connected with said intercommunication amplifier circuit, a circuit breaker connected with one terminal of each sound reproducer circuit and also connected with said relay, means associated with each unit for actuating the circuit breaker in the circuit of the loud speaker of the same unit and also for operating the circuit breaker in the circuit of the loud speaker at any other preselected unit, and means associated with each unit for energizing said relay, so as to selectively reverse the current flow through said sound reproducing devices while they are connected with said intercommunication amplifier circuit.

11. A multiunit radio receiving system comprising a plurality of receiving units operatively connected with the radio input circuit, an amplifier circuit for each unit including a normally closed circuit breaker, a sound reproducing device for each unit including a circuit having a normally closed circuit breaker connected with one of its terminals, an intercommunicating power circuit means common to all of said receiving units, an intercommunication amplifier connected with the first mentioned amplifier circuits and also with said intercommunication power circuit, a reversing relay connected with said intercommunication amplifying circuit, means connecting said reversing relay with the circuit of each sound reproducing devices, means associated with each unit for operating the first mentioned normally closed contacts to break the circuit to the sound reproducing device of the same unit, to break the circuit to the sound reproducing device of any other preselected unit, and also to break the amplifier circuit of said preselected unit, and control means associated with each unit for actuating said reversing relay, whereby the flow of current through the sound reproducing devices may be reversed while said devices are connected with said intercommunication power circuit.

12. A multiunit radio receiving system comprising a plurality of receiving units operatively connected with a common radio input circuit, each unit including a reproducing device and its operating circuit, a volume control circuit for each unit, normally closed contacts connected with one of the terminals of each of said sound reproducing devices, an intercommunication amplifier circuit means common to all of said receiving units, normally closed contacts in each of said sound reproducer circuits, a reversing relay having reversing contacts connected with the intercommunication amplifier circuit, means for connecting said relay contacts with a terminal of each of the sound reproducing devices, means for operating the circuit breakers to break the circuit to the sound reproducing device of said unit and to connect the same with said relay, and also to selectively break the circuits to the sound reproducing device of any other preselected unit, and control means associated with each unit for energizing said relay, whereby flow of current through the sound reproducers of any unit may be controllably reversed while said unit is connected with the intercommunication power circuit.

13. A multiunit radio receiving system comprising a plurality of receiving units operatively connected with a common radio input circuit, a sound reproducing device for each unit having

5 terminals connected with a sound reproducing circuit, a volume control circuit for each unit, a pair of relays associated with each unit, one of said relays of each unit being so connected with a terminal of the sound reproducing device of the same unit as to normally maintain a closed circuit to the latter, the other of said relays being connected with the volume control circuit of the same unit, an intercommunication amplifier circuit means common to all of said receiving units, 10 a relay having reversing contacts connected with said intercommunication amplifier circuits, means connecting the contacts of said relay with the contacts of each of said pairs of relays, so as to break the normal circuit to the affected sound reproducing device of that unit and also to break the normal volume control circuit of the preselected unit, and to establish circuit connections with the intercommunication amplifier circuit, 15 and means associated with each unit for actuating the reversing relay of the intercommunication amplifier circuit, whereby flow of current through the sound reproducing device of a unit may be controllably reversed.

20 14. A multiunit radio receiving system comprising a plurality of receiving units operatively connected with a common radio input circuit, a sound reproducing device for each unit having terminals connected with a sound reproducing circuit, a volume control circuit for each unit, a reversing relay, a set of relays for each unit, one being a speaker control relay and the other a control relay, said last mentioned relays each having two fixed contacts and one movable contact, the movable contact of the speaker control relay being connected with one terminal of the sound reproducer circuit of the same unit, one of the fixed contacts of the speaker control relay being connected with the movable contact of the 25 volume control relay, the other fixed contact of the speaker control relay being connected with a terminal of the reversing relay, one fixed contact of the volume control relay being connected to the opposite side of said reversing relay, and the other fixed contact of the volume control relay being connected with the volume control circuit of the same relay, a single operating device at each unit having means controlling the circuits to the speaker control relay of the same unit and the volume control relay of any other preselected unit, so as to break the speaker control and volume control circuits of the two last mentioned relays and to place them in circuit with the reversing relay, and means associated 30 with each unit for energizing said reversing relay whereby flow of current through the previously disabled sound reproducing devices may be controllably reversed.

35

15. In a multistation system, a plurality of program-selector units, means selectively controlled at each station for operatively connecting the station with any one of said program selector units, while the selected unit is operatively connected with any or all of the other stations, and in such manner that the sound-volume-producing-functions of said selected unit remain practically unimpaired irrespective of the number of stations connected therewith. 5
16. In a multistation system, a plurality of program-selector units, a plurality of operating circuits for the respective units there being one circuit for each unit, a plurality of circuit closers at each station selectively controlling all of said 10 circuits, said circuits and their circuit closers being so arranged that any one of the program-selector units may be selectively connected with any station while the selected unit is operatively connected with any one or all of the other stations, and in such manner that the sound-volume-producing-functions of the selected unit remain practically unimpaired irrespective of the number of stations connected therewith. 15
17. In a multistation system, a plurality of program-selector units, means selectively controlled at each station for operatively connecting the station with any one of said program selector units, while the selected unit is operatively connected with any or all of the other stations, and 20 in such manner that the sound reproduction functions of the various stations remain practically unimpaired irrespective of the number of stations connected therewith. 25
18. In a multistation system, a sound-reproducing element at each station, a plurality of program selection units, selective means at each station for operatively connecting the sound reproducing element with any one of said program selection units while said unit is operatively connected with any or all of the other stations, and in such manner that the sound-volume-producing functions of the selected unit remain practically unimpaired irrespective of the number of stations connected therewith. 30
19. In a multistation system, a sound-reproducing element at each station, a plurality of program selection units, selective means at each station for operatively connecting the sound reproducing element with any one of said program selection units while said unit is operatively connected with any or all of the other stations, and in such manner that the sound-volume-producing functions of the various stations remain practically unimpaired irrespective of the number of stations connected therewith. 35
